LOADING MECHANISM FOR PNEUMATIC GUNS

William S. Wells, Palo Alto, Calif., assignor to
Daisy Manufacturing Company, Plymouth,
Mich., a corporation of Michigan

Application January 26, 1948, Serial No. 4,295

3 Claims. (Cl. 124—51)

1

This invention relates to pneumatic guns and refers more particularly to improvements in loading mechanism for transferring shot from the delivery end of a shot retaining magazine to the barrel in advance of the shot positioning pin.

One of the objects of this invention is to provide a simple, compactly arranged mechanism responsive to withdrawal of the shot positioning pin from the gun barrel to transfer shot from the delivery end of the magazine to the barrel in advance of the pin so that return movement of the latter into the barrel advances the shot to its firing position in the barrel.

Another feature of this invention is to provide a pneumatic gun having cocking mechanism and having means connecting the latter mechanism with the positioning pin in such a manner that each time the gun is cocked, the firing pin is successively advanced into and retracted from the gun barrel. Inasmuch as the loading mechanism is operated in response to movement of the positioning pin, it follows that operation of the gun requires merely manipulating the operating means for the cocking mechanism, and as a result, operation of the gun is greatly simplified.

The foregoing as well as other objects will be made more apparent as this description proceeds, especially when considered in connection with the accompanying drawing, wherein:

Figure 1 is a fragmentary perspective view of a pneumatic gun having certain parts broken away for the sake of clearness;

Figure 2 is a side elevational view partly in section of the gun shown in Figure 1;

Figure 3 is a sectional plan view of a portion of the gun showing the various parts of the loading mechanism in one relative position;

Figure 4 is a view similar to Figure 3 showing the parts of the loading mechanism in another relative position;

Figure 5 is a sectional view taken substantially on the line 5—5 of Figure 2;

Figure 6 is a view similar to Figure 5 showing the parts in another position; and

Figure 7 is a sectional view taken on the line 7—7 of Figure 2.

For the purpose of illustration, the loading mechanism forming the subject matter of this invention is shown in connection with a pneumatically operated pistol type gun, although it will be understood as this description proceeds that the loading mechanism may also be installed on pneumatic guns of the rifle type.

In general the pneumatic gun shown in the drawings comprises a frame 10 and supporting structure 11 connected together for relative slid-

2

ing movement in opposite directions. As shown in Figures 1 and 2, a tube 12 is secured at the bottom of the frame in a position to telescopically receive a tube 13 secured to the bottom of the structure 10. The tube 12 is formed with a longitudinally extending slot 14 through the top wall of sufficient width to provide ample clearance for the joint between tube 13 and the adjacent part of the supporting structure.

10. A pistol grip 15 of suitable design is mounted on the frame adjacent the breech end thereof and a trigger guard 16 is secured to the bottom of the frame in advance of the grip. A trigger 17 is pivoted to the underside of the frame by a pin 18 having its axis extending perpendicular to the plane of the pistol enabling swinging movement of the trigger in said plane. The trigger has a finger engaging part 19 extending into the guard 16, and has an arm 20 projecting upwardly through registering slots in the bottom portions of the tubes 12 and 13. A suitable spring 21 is provided for urging the trigger 17 to the position shown in Figure 2 of the drawings wherein the finger engaging part is in its forwardmost position, and wherein the arm 20 projects into the tube 13 for engagement with the cocking mechanism.

In addition to the arm 20 on the trigger 17, the cocking mechanism comprises a plunger 21 and a coil spring 22. The plunger 21 is supported in the tube 13 on the structure 11 and is formed with enlargements 23 and 24 at opposite ends thereof. The enlargements slidably engage the inner wall of the tube 13 and the spring 22 is supported in the tube 13 in advance of the plunger. The rear end of the coil spring abuts the front enlargement 23 and the front end of the spring abuts an adjusting screw 25 threaded in the front end of the tube 13.

When the gun is in its uncocked or inoperative position (Figure 2) the enlargement assumes a position rearwardly of the arm 20 and the upper end of the latter projects into the forward path of travel of the enlargement 23. The arrangement is such that relative movement of the frame 10 and structure 11 in a direction away from each other engages the enlargement 23 with the arm 20 and swings the latter downwardly, enabling the enlargement 23 to pass forwardly over the arm. As soon as the enlargement 23 passes beyond the arm 20, the spring 21 returns the arm 20 to its projected position at the rear side of the enlargement 23 and prevents return movement of the plunger 21 when the frame 10 and structure 11 are relatively moved back to their normal positions. Thus the spring 22 is com-

pressed and the mechanism is held in a cocked position. The extent of relative movement of the frame 10 and structure 11 in directions away from each other is limited by a screw 26 threaded in a tapped hole formed in the frame and projecting into an elongated slot 27 formed in the bottom of the tube 12. The rear end wall of the slot engages the projecting end of the screw and acts as a stop to limit the extent of relative movement of the frame 10 and structure 11 in a direction away from each other.

As indicated above after the arm 20 on the trigger 17 is positioned at the rear side of the enlargement, the frame 10 and structure 11 are relatively moved to their normal positions. Upon relative movement of these parts to their normal positions, the enlargement 23 abuts the upper end of the arm 20, and the spring 22 is compressed or the gun is cocked. The spring 22 remains compressed until the arm 20 is forcibly disengaged from the enlargement by manipulating the trigger 17. The frame 10 and structure 11 are releasably held in their normal position by a latch arm 28 pivoted intermediate the ends on the frame between the grip 15 and trigger guard 16. The rear end of the latch arm 28 projects through a slot 29 in the tube 12, and is urged by a spring 31 into engagement with a shoulder 30 on the bottom of the tube 13. The forwardly projecting end of the arm 28 is positioned for engagement by the adjacent portion of the operator's hand in a manner such that a slight upward movement of the hand swings the arm 28 against the action of the spring 31 sufficiently to disengage the rear end of the arm 28 from the shoulder 30.

Supported at the breech end of the structure 11 is a block 32 having laterally spaced bores 33 and 34 extending longitudinally of the gun. The bore 33 forms the breech end of the gun barrel 35 and the bore 34 forms the breech end of the shot retaining magazine 36. The magazine 36 is in the form of a tube having the rear end removably sleeved in the front end of the bore 34 and having a clip 37 at the front end adapted to frictionally engage the barrel 35 adjacent the front end of the latter. As shown in Figure 6 of the drawings the barrel or bore 33 projects rearwardly beyond the delivery end of the bore 34 or manifold, and is formed with an opening 38 through the inner side of sufficient size to freely receive a shot 39. The opening 38 is connected to the delivery end of the magazine by a recess or pocket 40 formed in the top of the block 32 and having a length sufficient to accommodate one shot 39. In this connection attention is called to the fact that the shot are stored in the magazine in end to end relation, and are fed by gravity into the pocket 40 by elevating the forward end of the barrel.

The shot entering the pocket 40 from the delivery end of the magazine is transferred laterally into the bore 33 through the opening 38 by a transfer link 41 seated on the top of the block 32, and having the front end pivoted to the block by a headed pin 42 extending perpendicular to the barrel. Thus the rear end of the link 41 may swing in opposite directions in a horizontal plane. The side of the link 41 adjacent the magazine is provided with a rearwardly projecting extension 43 having a depending lug 44 extending into the pocket 40 through the top of the latter. The link 41 is normally retained in the position thereof shown in Figure 3 of the drawings wherein the lug 44 is positioned

at the outer end of the pocket 40 to retain the shot delivered by the magazine in the pocket. The link 41 is held in the above position against the action of a "hair pin" spring 45 having one end anchored on the block at 46 and having the other end abutting a shoulder on the swinging end of the link. The intermediate portion of the spring is looped around the pivot pin 42 below the head on the latter. The construction is such that when the link 41 is released from its retaining means about to be described, the spring 45 acts to swing the link in a direction to engage the lug 44 with a shot 39 in the pocket 40 at the delivery end of the magazine and transfer the shot into the barrel or bore 33 through the opening 38.

The link 41 is held in the position thereof shown in Figure 3 of the drawing against the action of the spring 45 by a cam stop 47 projecting upwardly from a rod 48 slidably supported in a bore 49 formed in the block 32 in parallel relation to the bores 33 and 34. The bore is longitudinally slotted to receive the stop 47, and is positioned to enable engagement of the stop with the side edge of the link 41 opposite the lug 44 when the frame 10 and structure 11 are in their normal positions shown in Figure 1 to 3 inclusive of the drawings. Thus swinging movement of the link 41 by the spring 45 from the position thereof shown in Figure 3 of the drawings in a direction to transfer shot from the delivery end of the magazine to the barrel is prevented by the stop 47.

The rear end of the rod 48 is connected to the upper end of a bridge part 50 positioned rearwardly beyond the block 32 and having the lower end anchored on the frame 10. Thus the rod 48 is moved with the frame 10 relative to the block 32 or link 41 upon relative movement of the frame 10 and structure 11 to cock the gun. Actually during relative movement of the frame 10 and structure 11 to cock the mechanism, the rod 48 is moved rearwardly in the bore 49 sufficiently to disengage the stop cam 47 from the link 41 as shown in Figure 4 of the drawings. As soon as the stop 47 releases the link the spring 45 acts to swing the link 41 in a direction to engage the lug 44 with a shot in the pocket 40 and to transfer the shot into the bore 33 through the opening 38. The extent of swinging movement of the link 41 by the spring 45 is limited by a shoulder 51 formed on the block 32 in a position to engage the rear end of the extension 43 on the link 41.

The edge of the link 41 engaged by the stop 47 is formed with a laterally inwardly curved cam surface 53 at the rear end of the link 41. In the position of the parts shown in Figure 4, the cam surface 53 is located by engagement of the extension 43 with the shoulder 51 in a position to engage the stop 47 as the frame 10 and structure 11 are relatively moved to their normal positions. As shown in Figure 4 of the drawings, the stop 47 engages the cam surface 53 and swings the link against the action of the spring 45 back to its normal position shown in Figure 3 of the drawings as the frame 10 and structure 11 are returned to their normal positions. It follows from the above that cocking the gun subsequent to firing the latter also automatically transfers a shot from the delivery end of the shot retaining magazine to the gun barrel.

The shot introduced by the link 41 into the bore 33 through the opening 38 must be advanced in the barrel to its firing position or to a position

in advance of the pressure discharge port 54 shown in Figures 2 and 6 of the drawings. This is accomplished herein by a positioning pin 55 secured at its rear end to the bridge part 50 and having the front end slidably engaging in the barrel or bore 33. The length of the pin 55 is such that when the frame 10 and structure 11 are relatively moved to the positions shown in Figures 4 and 6 of the drawings, the front end of the pin assumes a position in the bore 33 rearwardly of the shot receiving opening 38. Thus as the frame 10 and structure 11 are relatively moved to their normal positions, the shot previously transferred from the magazine through the pocket 40 into the bore 33 in advance of the pin 55 is moved forwardly by the pin 55 to a position in the barrel in advance of the pressure discharge port 54.

When the pin 55 is in its forwardmost position in the barrel, shot in the magazine is prevented from dropping into the pocket 40 by a lug 57 extending laterally outwardly from the pin 55 and movable through a slot 59 formed in the part of the block which forms the rear side of the pocket 40. Thus, when the gun is held in an inclined position with the muzzle end elevated, the pellets slide downwardly in the magazine and the lowermost pellet rests on the lug 57. When the action is manipulated to withdraw the pin 55, the lug 57 moves away from the delivery end of the magazine and allows the end pellet to drop into the pocket 40. At the same time the extension on the link 41 swings inwardly and transfers the pellet into the barrel in advance of the pin 55. In actual operation it is found that the lug 57 not only serves to maintain the pellets in the magazine when the action is closed but also coacts with the transfer link 41 to disengage the forward end of the rearwardmost pellet from the skirt portion of the adjacent pellet without deforming the pellets.

In order to impart a neat and pleasing appearance to the gun, the block 32 and associated parts are concealed by a cap 60 of sheet metal. The cap 60 is of inverted U-shape in cross section and may be slipped over the block 32 in the manner clearly shown in Figure 1 of the drawings. The opposite sides of the cap are frictionally or otherwise secured to the block 32 so as to form a unit with the structure 11.

The means for introducing air under pressure into the barrel through the port 54 to propel the shot 39 through the barrel at the desired velocity forms no part of this invention and need not be described in detail. Briefly the structure 11 embodies storage space 61 for air under pressure replenished as required by a suitable compressor (not shown) which may be a unit separate from the gun or embodied in the latter. In any case the rear end of the storage space has an outlet port 62 surrounded at the inner side of the space by a flat seat 63 and connected to the port 54 by a passage 64. A valve member 65 is suitably supported for sliding movement in the storage space and is held against the seat 63 by the pressure of the air in the storage space assisted by a relatively weak positioning spring 66.

The valve member 65 is momentarily moved away from its seat to admit a limited quantity of air under pressure to the discharge port 54 by a plunger 67 slidably supported in the block 32 and having the front end abutting the valve member 65. The rear end of the plunger 67 abuts the upper end of a rock arm 68 having the lower end extending to a position at the rear

end of the tube 13 adjacent the enlargement 24 on the rear end of the plunger 21. The rock arm is pivoted intermediate the ends on the rear end of the block 32 by a pin 69 and is normally urged by a relatively weak spring 70 in a direction to hold the plunger 67 against the valve member 65.

The above construction is such that the valve member 65 is normally held against its seat 63, and the enlargement 24 at the rear end of the plunger 21 is spaced forwardly from the lower end of the rock arm 68 when the spring 22 is compressed or when the gun is cocked. Thus manipulation of the trigger 17 releases the arm 20 on the trigger from the enlargement 23 and permits the spring to throw the plunger 21 rearwardly in the tube 13. As the enlargement 24 at the rear end of the plunger 21 approaches the rear end of the tube 13, it strikes against the lower end of the arm 68 and suddenly swings the latter in a clockwise direction. As a result the upper end of the arm is moved forwardly and applies a forward thrust on the plunger 67 sufficient to momentarily move the valve member 65 off its seat. The extent to which the valve member 65 moves away from its seat depends upon the pressure of the air in the storage space resisting movement of the valve member so that substantially uniform air pressure is supplied to the barrel for a given number of shots.

Operation

Assuming that the various parts of the gun are in their relative positions shown in Figure 2 of the drawings and that it is desired to cock the gun, the operator grasps the grip 15 in one hand in the usual manner and places the other hand over the barrel portion. The hand engaged with the grip 15 is shifted upwardly slightly to swing the latch arm 28 against the action of the spring 31 and release the rear end of the arm from the shoulder 30. Upon release of the latch the frame 10 on which the grip 15 is mounted and the structure 11 are relatively moved in a direction away from each other until the upper end of the screw 26 engages the rear wall of the slot 27. During this relative movement the enlargement 23 on the plunger 21 passes over the arm 20 on the trigger and the rod 48 as well as the pin 55 are retracted in their respective bores formed in the block 32 on the structure 11. As the stop 47 moves rearwardly with the rod 48 out of engagement with the link 41, the latter is swung by the spring 45 to the position shown in Figure 4 of the drawings, and a shot 39 is moved by the lug 55 44 on the link into the bore 33 through the opening 38 to a position in the barrel in advance of the pin 55. It will, of course, be understood that the gun is tipped upwardly just prior to the cocking operation to permit a shot 39 from the delivery end of the bore 34 to enter the pocket 40 at the inner side of the lug 44 depending from the swinging end of the link.

Upon completion of the above operation, the frame 10 and structure 11 are relatively moved in a direction toward each other. As the above parts are returned to their normal positions, the enlargement abuts the arm 20 on the trigger 17, and the spring 22 is compressed. Also the latch arm 28 is swung by the spring 31 to a position wherein the rear end of the arm engages the shoulder 30 to latch the frame 10 and structure 11 in their normal positions. It will further be noted that during return movement of the parts the pin 55 advances the shot 39 in the breach 75 end of the gun barrel to a position in advance

of the pressure port 54, and at the same time, the stop 47 engages the cam surface 53 on the rear end of the link 41 to return the latter to its normal position shown in Figure 3 of the drawings.

The shot 39 positioned in the above manner may be fired by swinging the arm 19 on the trigger 17 rearwardly in the usual manner. This action releases the arm 20 from the enlargement 23 and permits the spring 22 to throw the plunger 21 rearwardly against the lower end of the rock arm 68. As a result, the upper end of the rock arm is thrust forwardly against the plunger 67 and the valve member 65 is displaced from its seat to admit air under pressure into the gun barrel at the rear end of the shot 39 in the barrel.

What I claim as my invention is:

1. Loading mechanism for a pneumatic gun comprising supporting structure, a barrel on said structure having provision at the breech end for receiving shot, a shot retaining magazine on the structure at one side of the barrel, a shot receiving pocket connecting the breech end of the magazine with the barrel and open at the top; including a link pivoted at its front end on the supporting structure for swinging movement about an axis perpendicular to the barrel and magazine, means at the swinging end of the link extending into the pocket through the open top of the latter and adapted to assume a position in the pocket laterally outwardly from the delivery end of the magazine to enable shot from the magazine to enter the pocket at the inner side of said means, spring means for urging the swinging end of the link in a direction to transfer shot from the delivery end of the magazine into registry with the barrel, a pin movable into the breech end of the barrel from a position rearwardly of the pocket to advance shot forwardly in the barrel, a member movably supported on said structure and connected with the pin, a cam surface on the swinging end of the link, said member being engageable with said cam surface in the forwardmost position of the pin to hold the link in the position aforesaid thereof against the action of the spring means, said cam surface being contoured to permit inward swinging movement of the link by the spring means to transfer shot from the magazine to the barrel in response to withdrawal of the pin from the barrel.

2. Loading mechanism for a pneumatic gun comprising supporting structure, a barrel on said structure having an opening in the inner side at the breech end of sufficient size to freely receive shot, a shot retaining magazine on the structure at one side of the barrel and having the delivery end thereof adjacent the shot receiving opening in the barrel, a pocket extending transversely of the structure in a position to connect the delivery end of the magazine to the shot receiving opening and open at the top; including a link pivoted at its front end on the supporting structure at the top of the barrel and magazine for swinging movement about an axis perpendicular to the barrel, a depending part at the swinging end of the link extending into the pocket through the open top of the latter and adapted to assume a position in the pocket laterally outwardly from the delivery end of the magazine, spring means for urging the swinging end of the link in a direction to move said part inwardly in the pocket and transfer shot from the delivery end of the magazine into registry with the shot receiving opening in said barrel, a pin slidably

mounted in the supporting structure and movable forwardly into the barrel for advancing shot along the barrel and adapted to be withdrawn from the barrel to a position wherein the front end of the pin is located rearwardly of the shot receiving opening in the barrel, a stop movably supported on said structure and connected with the pin for engaging the link in the forwardmost position of the pin to hold the link in the position aforesaid thereof against the action of the spring means, and a cam surface on the swinging end of the link engageable with the stop upon withdrawal of the pin to permit inward swinging movement of the link by the spring means and engageable with the stop upon forward movement of the pin to swing the link outwardly against the action of the spring means to the position aforesaid thereof.

3. Loading mechanism for a pneumatic gun comprising supporting structure, a barrel on said structure having provision at the breech end for receiving shot, a shot retaining magazine on the structure at one side of the barrel, a pocket at the rear end of the magazine for receiving shot delivered by the magazine and extending laterally to the barrel, a unit supported for sliding movement relative to the supporting structure fore and aft of the barrel, a link provided at its front end on the supporting structure at the top of the barrel and magazine for swinging movement about an axis perpendicular to the barrel, a part on the swinging end of the link normally located in an inoperative position in the pocket at the outer side of the delivery end of the magazine, spring means for urging the swinging end of the link in a direction to move said part inwardly through the pocket to transfer shot from the delivery end of the magazine into registry with the barrel, means responsive to relative movement of said unit and structure in one direction to permit swinging movement of the link by the spring means in a direction to transfer shot from the pocket into the barrel and responsive to relative movement of said unit and structure in the opposite direction to return the link to the inoperative position aforesaid, a pin slidably mounted in said supporting structure for movement forwardly into the barrel so as to advance shot along the barrel, as well as movement rearwardly in the barrel to a position wherein the front end of the pin is located rearwardly of the shot receiving opening in the barrel, and stop means connected with said pin for closing the pocket at the rear end of the magazine when the pin is in its forwardmost position and for opening the pocket when the pin is in its rear position so as to permit shot to be transferred from the magazine to the barrel, as set forth aforesaid.
